United States Patent Office

Des. 193,196
Patented July 10, 1962

193,196

GAME BOARD

Clifford Q. Brodie, 3820 Cerrito Ave., Oakland, Calif.

Filed Nov. 1, 1961, Ser. No. 67,329

Term of patent 14 years

(Cl. D34—5)

The FIGURE is a plan view of a game board of conventional thickness, showing my new design.

I claim:

The ornamental design for a game board, substantially as shown and described.
